UNITED STATES PATENT OFFICE.

DANIEL EDWARD HENNESSY, OF MILWAUKEE, WISCONSIN, ASSIGNOR, BY MESNE ASSIGNMENTS, TO THE FISK RUBBER COMPANY, OF CHICOPPEE FALLS, MASSACHUSETTS, A CORPORATION OF MASSACHUSETTS.

MOLD.

Application filed August 19, 1921, Serial No. 493,591. Renewed February 27, 1924.

To all whom it may concern:

Be it known that I, DANIEL EDWARD HENNESSY, a citizen of the United States, and a resident of Milwaukee, in the county of Milwaukee and State of Wisconsin, have invented certain new and useful Improvements in Molds, of which the following is a specification.

My invention relates to molds and the principal object of my invention is to provide a new and improved mold. In the drawings accompanying this specification and forming a part thereof I have shown, for purposes of illustration, one form which my invention may assume. In these drawings:

Figure 1 is a vertical section of a heater showing this illustrative embodiment of my invention,

20 Figure 2 is a plan view of the mold shown in Figure 1,

Figure 3 is a section on the line 3—3 of Figure 2, while

25 Figure 4 is a section similar to Figure 3 showing an alternative form of mold.

In the drawings I have shown a heater 11 comprising a shell 12 supporting a top ring 13, a ram 15 supporting a table 16 which carries an annular plate 17, and a 30 heater cover 14 carrying a similar plate 18. Between the plates 17 and 18 are clamped a plurality of molds 19.

Each of the molds 19 is provided with a plurality of vents 20 terminating in a channel 21 cut in the two halves of the mold and closed when the mold is closed, and with two 35 series of side channels 22 each terminating in a channel 23. The upper face 24 of each mold 19 is provided with a pair of packing rings 25 flanking the channel 23 thereof and each comprising a dovetail portion 26 adapted to seat in a corresponding depression 27 in the mold 19 and a projecting portion 28 adapted to engage the surface of an abutting 40 body. The plate 17 of the table 16 is provided with similar rings.

In carrying out certain processes of vulcanization wherein pressure is applied to the interior of the article during vulcanization 45 it is necessary to protect the vent holes from the action of this pressure and this is ordinarily done by confining the pressure within a duct. I find that the same result may be accomplished by segregating the

vents. It will be apparent that in the apparatus just described the center vents 20 are segregated upon closing of the mold and the side vents 22 are segregated by superimposition of the molds upon the plate 17 and of the top plate 18 upon the top mold 19. Accordingly, it will be apparent that the apparatus herein disclosed accomplishes the segregation of the vents.

Under certain conditions it may be desirable to construct each mold as a separate unit and in such case the side vents 22 may lead into channels 29 similar to the channels 23 but each provided with shoulders 30 adapted to receive a packing ring 31 which acts to effectively close the open face of the channel 29.

While I have described herein one embodiment of my invention and an alternative therefor the disclosure herein is illustrative only and my invention is not limited thereto.

I claim:

1. In combination, a mold provided with vents opening through a face thereof, and means adapted to segregate said vents.

2. In combination, a mold provided with vents opening through a face thereof, and means adapted to form a chamber over the vent openings to thereby segregate the vents.

3. In combination, a mold provided with vents opening through a face thereof, and a plate adapted to overlie the openings of said vents.

4. In combination, a mold provided with vents opening through a face thereof, and a plate adapted to overlie the openings of said vents and channelled to provide a closed chamber into which said vents communicate.

5. In combination, a mold provided with vents openings into a channel in one face thereof, and a plate adapted to overlie said channel to thus form said channel into a closed chamber.

6. In combination, a pair of molds each provided with vents opening through the adjacent face thereof, and means whereby the space into which said vents open is formed into a chamber.

7. In combination, a mold provided with vents opening into a channel in one face thereof, and a second mold having vents opening into one face thereof and adapted to be superimposed upon said first mold so that the vents open into the channel of the

- first mold and said second mold closes said channel.
8. A mold having vents opening into a channel in one face thereof, and a plate adapted to close said channel.
9. In combination, a mold provided with vents opening through an exterior surface thereof, and means adapted to segregate said vents.
10. In combination, a mold provided with vents opening through an exterior surface thereof, and means adapted to form a chamber over the vent openings to thereby segregate the vents.
11. In combination, a mold provided with vents opening through an exterior surface thereof, and a plate adapted to overlie the openings of said vents and channelled to provide a closed chamber into which said vents communicate.
12. In combination, a mold provided with vents opening into a channel in an exterior surface thereof, and a plate adapted to over-
- lie said channel to thus form said channel into a closed chamber.
13. In combination, a pair of molds each provided with vents opening through the adjacent exterior surface thereof, and means whereby the space into which said vents open is formed into a chamber.
14. In combination, a mold provided with vents opening into a channel in one exterior surface thereof, and a second mold having vents opening into one exterior surface thereof and adapted to be super-imposed upon said first mold so that the vents open into the channel of the first mold and said second mold closes said channel.
15. A mold having vents opening into an exterior channel in one exterior surface thereof, and a plate adapted to close the said channel.

In testimony whereof I have signed my name to the above specification.

DANIEL EDWARD HENNESSY.
